UNITED STATES PATENT OFFICE

166,061

COMBINATION BATHROOM UNIT

Landrum E. Bagwell, Brevard, N. C.

Application February 10, 1951, Serial No. 14,166

Term of patent 14 years

(Cl. D4—4)

To all whom it may concern:

Be it known that I, Landrum E. Bagwell, a citizen of the United States, residing at Brevard, in the county of Transylvania and State of North Carolina, have invented a new, original, and ornamental Design for a Combination Bathroom Unit, of which the following is a specification, reference being had to the accompanying drawings, forming part thereof.

Figure 1 is a perspective view of a combination bathroom unit, showing my new design; Figure 2 is a perspective view thereof taken from the end opposite Figure 1, the cabinet door being shown in partly open position; and, Figure 3 is a fragmentary view of the end of my unit showing the commode in side elevation. The back of the bathroom unit is plain.

I claim:

The ornamental design for a combination bathroom unit, substantially as shown and described.

LANDRUM E. BAGWELL.
